UNITED STATES PATENT OFFICE

127,619

DESIGN FOR A LINE BLIND

Leland S. Hamer, Long Beach, Calif.

Application January 21, 1941, Serial No. 98,233

Term of patent 14 years

To all whom it may concern:

Be it known that I, Leland S. Hamer, a citizen of the United States, residing in the city of Long Beach, in the county of Los Angeles and State of California, have invented a new, original, and ornamental Design for a Line Blind, of which the following is a specification, reference being had to the accompanying drawing, forming part thereof.

The figure is a perspective view of a line blind showing my new design, the opposite side and end presenting substantially the same appearance as the side and end shown.

I claim:

The ornamental design for a line blind, as shown and described.

LELAND S. HAMER.
